COMBINED BOTTLE AND CAP THEREFOR

John E. Beeby, Lafayette, Calif., assignor to The Clorox Company, Oakland, Calif., a corporation of Ohio

Filed Mar. 21, 1969, Ser. No. 16,383

Term of patent 14 years

Int. Cl. D9—01

U.S. Cl. D9—96

FIG. 1

FIG. 2

FIG. 3

FIG. 1 is an elevational view of a combined bottle and cap therefor embodying my new design, with a section broken away to show the contour of the bottom; FIG. 2 is a top plan view; and

FIG. 3 is a bottom view thereof.

The characteristic feature of my design resides in the configuration of the neck bulge and cap elements for a generally cylindrical container as shown.

I claim:

The ornamental design for a combined bottle and cap therefor, substantially as shown and described.
